LAMP EXHAUST HEAD

Ernest E. Yeo, Wenham, and David P. Drown, Beverly, Mass., assignors to Sylvania Electric Products Inc., Salem, Mass., a corporation of Massachusetts

Application June 16, 1955, Serial No. 515,852

3 Claims. (Cl. 141—384)

Our invention relates to machinery useful in making incandescent lamps and in particular to an improved exhaust head by means of which an individual lamp may be mounted for the automatic exhausting, flushing and filling operations performed on the rotating turret of a conventional "exhaust machine."

In the normal process of lamp manufacture a mount comprising a stem, a filament and an exhaust tube is assembled into a bulb and the two are flame sealed. Then the lamp is transferred to an exhaust machine where appropriate instrumentalities operate to exhaust the bulb, flush the bulb with nitrogen and then fill the bulb with an inert gas. Customarily the exhaust machine comprises a rotating turret with a number of heads into which the bulbs are clamped, the heads communicating with sweeps terminating in the interior of the machine in ports which are brought successively into communication with the several exhaust and gas manifolds. Inasmuch as there are occasional breakages of bulbs or mounts taking place in the machinery preceding the exhaust machine, it happens from time to time that an exhaust head will not receive a lamp; it is therefore necessary to have a valve in each head in order that the empty heads can be sealed off.

Inevitably dirt and dust are sucked into the exhaust heads from the lamps, and it is therefore frequently necessary to dismount the heads for cleaning. Moreover the low pressures involved lead inescapably to failures of even the best valves and seals. In the past it has been an expensive and time consuming operation to take apart the heads either to clean them or to renew valves or sealing elements, since the entire machine is necessarily shut down for a rather lengthy period.

The most important object of our invention is to improve the efficiency of lamp making machinery.

Another object of the invention is to facilitate the operations of cleaning or repairing exhaust valve heads.

An important feature of our invention resides in a self-contained unitary head adapted to be mounted on an exhaust machine by a single bolt and including in addition to means for clamping and sealing the exhaust tube of a lamp, an easily accessible filter and a simple, easily removable valve.

We have found in practice that an exhaust machine equipped with the improved heads of our invention may be provided with a number of spare heads, and a head which becomes defective for any reason can be replaced in about thirty seconds, thus reducing to an absolute minimum the time during which the exhaust machine must be stopped in the event of any difficulty with any of the heads. Furthermore, in the event the valve of a head becomes defective, usually by the deterioration of a sealing ring, the valve may be removed and replaced in a matter of a few seconds. Consequently the efficiency of the machine is greatly increased, as will be appreciated by those familiar with machinery operating at very high rates of production.

These and other objects and features of the invention will be more readily understood and appreciated from the following detailed description of a preferred embodiment thereof selected for purposes of illustration and shown in the accompanying drawing, in which:

Fig. 1 is a view in cross-section through an exhaust head constructed in accordance with the invention, and

Fig. 2 is a bottom plan of the exhaust head shown in Fig. 1.

As will be apparent from an inspection of Fig. 1, the exhaust head of our invention is organized about a compact aluminum casing 16 which is mounted upon the external rim or turret 10 of an exhaust machine equipped with a plurality of radially extending sweeps 12 which project through the turret rim 10. The casing 16 is secured to the rim 10 by means of a single bolt 18 and a centering stud 20 set into the rim 10 and extending into an appropriate hole in the face of the exhaust head. Extending through the casing is a transverse bore 22 enlarged at the inner end of the casing 16 to receive a metal bushing 24 provided with an internal wall 26 having a relatively small central aperture 28. The bushing 24 is sealed in air-tight relation to the casing 16 by means of two spaced rubber sealing rings 30. The exhaust sweep 12 is received in the inner end of the bushing 24 and an air-tight seal is secured by means of a rubber sealing ring 14 contained in a groove cut adjacent the end of the exhaust tube 12.

Adjacent the wall 26 of the bushing 24 is a downwardly extending port 32 in alignment with a passage 34 cut into the interior of the casing 16 and leading to a relatively large internal chamber 36 which serves to accommodate a porous bronze filter member 38. The sealing rings 30 span the wall 26 and the port 32. The chamber 36 forms an opening at the bottom of the casing 16 which is normally closed by a bottom cover 40 having outwardly extending ears 39 through which bolts are passed into the casing 16 so that the cover may be drawn tightly against the bottom of the casing 16, a sealing ring 41 being interposed between the two members to provide an air-tight seal between the two. The bottom cover 40 also has an upwardly projecting flange which fits into the chamber 36 and bears against the filter 38 to hold it in position.

The bottom cover 40 has a central vertical passage 42 opening into the chamber 36 and embraced by a thick relatively soft rubber ring 44. The bottom cover 40 is externally threaded to receive a clamp 46 which includes a thrust block 51 bearing against the bottom of the rubber ring 44 and supported in bearings 50 mounted at the bottom of the clamp 46. For operating the clamp there is provided a lever 48 which is secured in fixed relation to the clamp and adapted to be operated by external means (not shown), a stop member 49 being provided on the bottom cover 40 to limit the opening movement of the lever 48.

In the normal operation of the machine, a lamp is presented upside down to the head and thrust upwardly so that its exhaust tube passes through the rubber ring 44. Then the lever 48 is operated to rotate the clamp member and compress the rubber ring tightly around the exhaust tube so that the lamp is then held firmly in position and in air-tight sealing relation with the interior of the bottom cover 40 and the casing 16.

Mounted for reciprocation in the bore 22 of the casing 16 is a valve plunger 54 having an enlarged inner head on which is mounted a sealing ring 56 of slightly larger normal diameter than that of the interior of the bushing 24 into which the head of the plunger extends. Mounted on the extreme inner end of the plunger 54 is a rubber sealing ring 58 of sufficient diameter to embrace the aperture 28 formed in the wall 26 in the bushing, when

the valve plunger is at its extreme inner position, thrust against the wall 26. Surrounding the intermediate portion of the valve plunger 54 is a spiral compression spring 60 bearing at its inner end against the enlarged head of the plunger and at its outer end upon the inner surface of a collar 62 slidably mounted upon the valve plunger 54 and limited in its movement thereon by means of a pin 64 passing through the collar and through an elongated slot 66 cut through the valve plunger 54. A pivot pin 68 passing through the outer end of the valve plunger 54 provides pivotal support for a cam lever 70 which embraces the end of the valve plunger and extends outwardly therefrom. The cam lever 70 is so dimensioned that when it is moved to the position shown in Fig. 2 the valve plunger 54 is retracted, as shown in Fig. 1, opening the aperture 28 in the wall 26 and thus placing the exhaust tube of the lamp into communication with the sweep 12. However, when the lever 70 is moved upwardly from the position shown in Fig. 2 so that the surface 100 bears on the collar 62, the spring 60 acts to thrust the valve plunger 54 inwardly of the casing 16 and urges the sealing ring 58 tightly into contact with the surface of the wall 26, thus closing the aperture 28.

In order to hold the valve in proper operating position, there is provided a keeper 72 surrounding the head of the bolt 18 and projecting downwardly to engage a shoulder cut into the upper face of the collar 62. In order to remove the valve, it is only necessary to loosen the nut 102 on the end of the bolt 18 and slide up the keeper 72. The valve plunger and its associated elements can then be withdrawn entirely from the head; or the head may be totally removed as a unit from the machine by removing the nut. The result is considerable flexibility in operation, since in order to install a spare head it is necessary only to remove the nut 102, slide the casing 16 outwardly of the rim 10, slide a new head onto the bolt 18 (centering it by the pin 20) and then replacing the nut 102. As previously explained, the valve plunger can be replaced even more simply by loosening the same nut 102.

In normal operation the turret 10 is rotated into position to receive a lamp, at which time the valve is closed and the clamp is opened. If a lamp is then inserted into the head with its exhaust tube 110 passing through the rubber ring 44, the next operation is to rotate the clamp lever 48 in order to clamp and seal the lamp into the head and then to operate the cam lever 70 to open the valve. If no lamp is presented to the head, the cam lever 70 is not actuated so that the valve remains closed.

Although the embodiment of our invention shown in the drawings and described above represents the best

mode now known to us for practicing the invention, it will be obvious to those skilled in the art that the head may be modified in several respects without departing from the spirit of the invention as defined in the appended claims.

We claim:

1. An exhaust head for lamp-making machinery, comprising a casing having a through-and-through bore, the bore being enlarged adjacent one end to receive a bushing, 10 a pair of spaced resilient sealing members interposed between said bore and the bushing, an apertured partition disposed internally in said bushing and disposed between said sealing members, an inlet passage formed in said casing and extending through said bushing adjacent said partition and between said sealing members, said bushing being adapted to receive at one end an exhaust pipe on the side of the partition opposite the inlet passage, a valve plunger received in the bore and bushing, sealing means carried by said plunger effective to touch said partition and close said aperture, cam operated means 15 effective to retract the valve plunger to open said aperture, and spring means normally urging the plunger inwardly to closed position.
2. An exhaust head for lamp-making machinery, 20 comprising a casing having a bore, an apertured partition in said bore, a passage communicating with said bore adjacent said partition, a valve plunger received in said bore, a resilient sealing member carried at the inner end of said plunger to seal the aperture in said partition when the plunger is thrust inwardly, a resilient sealing ring 25 mounted on said plunger, resilient means normally urging said valve plunger inwardly to closed position, cam operated means for retracting said plunger, and means for releasably clamping the exhaust tube of a lamp into communication with said passage.
3. An exhaust head for lamp-making machinery, comprising a casing having a first bore for receiving the end of an exhaust line, and a second bore, an apertured wall 30 separating said bores, an inlet passage communicating with said second bore, said casing also having a chamber communicating with said inlet passage, a filter mounted in said chamber, a valve plunger received in the second bore, sealing means mounted on said plunger for closing the aperture in said wall when the plunger is thrust inwardly, cam operated means for reciprocating the plunger, and means for clamping the exhaust tube of a 35 lamp into communication with said chamber.
